UNITED STATES PATENT OFFICE.

EDUARD MERZINGER, OF DRESDEN, GERMANY.

PRESS-BUTTON FASTENER.

Application filed March 25, 1926, Serial No. 97,382, and in Czechoslovakia February 3, 1926.

This invention is an improvement in or relating to press button fasteners, the stud member of which is secured to the material or support by inserting into it the pointed end of a fastener that is passed through the said material and is caused to curl up inside the stud. The present invention consists in providing the solid, needle-like shank of the fastener with a flattened portion of 5 lanceolate shape near its point, which portion is bent sideways so that it will be positively guided on being inserted into the dome of the stud instead of being rolled up therein in a haphazard manner.

10 A construction of the fastening is illustrated by way of example in the accompanying drawing.

Figures 1 and 2 are two views of the needle-like shank,

20 Figure 3 is a section on line $x-x$ in Figure 1, and

Figure 4 shows in section a press button secured on cloth or other material.

The stud 1 of the press button is dome-shaped and is fastened to the material in the known manner by rolling up in the dome, by pressure, a solid needle-like shank 25 3 introduced from the back of the material. The shank 3 has a head or disc 2.

According to the invention, the shank 3 is provided behind its point 4 which is bent to the side, with a flattened lanceolate portion 5 which, owing to its being guided immediately against the inside surface of the dome, induces the rolling-up movement of 35 the shank.

What I claim is:—

In a press-button fastener, the combination of a dome-shaped stud, and a fastening member for securing it to its supporting material; said member embodying a solid, needle-like shank adapted to be passed through the material and terminating in a transversely flattened, lanceolate portion which tapers to a point at its apex and also 40 tapers at its base and which is adapted to curl up in the dome when its pointed apex strikes against the curved inner surface of the dome and to be positively guided in its curling by such surface, said lanceolate portion 45 being curved laterally in the same general direction as the aforesaid dome surface so as to assist the curling action. 50

In testimony whereof I affix my signature.

EDUARD MERZINGER.
